UNITED STATES PATENT OFFICE

2,067,199

BLOCKOUT MECHANISM FOR DUPLICATING MACHINES

Alfred Marchev, La Grange, Ill., assignor to Ditto, Incorporated, Chicago, Ill., a corporation of West Virginia

Application January 10, 1936, Serial No. 58,523

18 Claims. (Cl. 101—132)

This invention relates to duplicating machines and is particularly adapted to be embodied in a duplicating machine wherein copy sheets are brought into contact with a master sheet, a suitable solvent for the ink or carbon on the master sheet being employed so that the data on the master sheet will be transferred to the copy sheet.

The master sheets have the data to be duplicated formed thereon in reverse so that, when a portion of the carbon or ink is dissolved off by the volatile fluid and transferred to the surface of the copy sheet, it will appear in correct readable form.

According to one type of machine to which this invention is applicable, a volatile solvent such as alcohol is employed, and this solvent is applied to the surface of the copy sheets as they approach the master sheet so that the master sheet and copy sheet may be placed in intimate contact before the solvent has had time to evaporate.

Certain forms of the invention are embodied in a machine of the type shown and described in the application of John W. Hernlund, Serial No. 44,911, filed October 14, 1935, for Duplicating machines. This machine comprises a rotary drum having means for clamping master sheets thereto and for discharging them therefrom. The copy sheets may be advanced to the drum in any suitable manner, and a platen roller is adapted to press the copy sheets against the master sheet during the duplicating operation. Moistening means and copy sheet advancing means comprises combined moistening and feeding rollers adjacent the drum and operated in timed relation thereto for advancing the copy sheet to the platen roller and drum and at the same time applying the necessary solvent to one surface of the copy sheet to dissolve ink from the master sheet upon the drum.

The improved machine herein disclosed comprises means whereby the master sheet may be attached to and removed from the drum, and means whereby block-out sheets for preventing transfer of a certain portion of the copy on the master sheet may be superimposed and held upon the master sheet at the will of the operator.

Means are also provided whereby the operator may control a master sheet laying tray so as to bring it into registry with master sheet gripping means on the drum at a stationary position of the gripping means.

Means are also provided whereby the operator may, by a simple movement of a control lever, release a master sheet or stop the drum in the

master sheet receiving position with the old master sheet still in place and apply a block-out sheet or a new master sheet, or leave the old master sheet undisturbed as he may desire.

Other features and advantages of the invention will become apparent as the following description progresses, reference being had to the accompanying drawings wherein—

Fig. 1 is a plan view of a duplicating machine which embodies the invention;

Fig. 2 is a vertical sectional view taken substantially on the line 2—2 of Fig. 1;

Fig. 3 is a sectional view taken substantially on the line 3—3 of Fig. 1;

Fig. 4 is a fragmentary sectional view taken on the line 2—2 of Fig. 1 showing a changed position of the mechanism from that illustrated in Fig. 2;

Fig. 5 is a fragmentary sectional view taken on the line 2—2 of Fig. 1 showing the mechanism in a further position;

Fig. 6 is a fragmentary sectional view taken on the line 2—2 of Fig. 1 showing the mechanism in a further position;

Fig. 7 is a fragmentary sectional view taken on the line 2—2 of Fig. 1 showing a further position of the mechanism;

Fig. 8 is a fragmentary plan view of a portion of the mechanism;

Fig. 9 is a fragmentary sectional view similar to Fig. 4 showing a modified form of the invention;

Fig. 10 is a fragmentary sectional view like Fig. 9 showing the modified parts in a different operative position;

Fig. 11 is a fragmentary sectional view like Fig. 9 showing the modified parts in a third position;

Fig. 12 is a fragmentary plan view of the modified form of the invention; and

Fig. 13 is a fragmentary plan view of a part of the mechanism shown in Fig. 12, certain parts being in section to illustrate the structure more clearly;

Fig. 14 is a fragmentary sectional view showing a further modification.

Referring now in detail to the drawings, in which a preferred embodiment of the invention is shown, reference characters 14 and 15 designate a pair of side frames adapted to rest upon any suitable support, these side frames 14 and 15 being provided with rubber feet 16 and 17. The side frames are suitably secured together by brackets, not shown. A duplicating drum 18 is supported from the side frames by a shaft 19, 55

Cooperating with the drum 18 is a master sheet guide or tray 20 and a copy sheet feed table 21. A moistening receptacle 22 is provided with a moistening felt or wick 23 adapted to supply moisture to a combined feeding and moistening roller 24. A second roller 25 cooperates with the roller 24 in feeding copy sheets to the drum 18. For pressing the copy sheets against a master sheet on the drum, a platen roller 26 is carried by the side frames of the machine in a manner more fully described in the application hereinbefore identified.

The details of the moistening mechanism and copy sheet feeding mechanism form no part of the present invention and hence will only be described generally in order to enable one to understand the application of the present invention to a machine of this type.

The platen roller 26 is not independently driven, but is rotated by its contact with the drum 18 or with sheets interposed between it and the drum 18. A gear 27 is secured to one end of the drum 18 and drives an idler gear 28 which in turn drives a gear 29 fixed to the moistening roller 24. The moistening roller 24 is thus driven in timed relation to the drum, and its cooperating roller 25 is driven by contact with the roller 24 or a sheet of paper interposed between the rollers.

The drum 18 is adapted to be intermittently driven, as disclosed in the prior application, from a suitable source of power not shown. The mechanism whereby the rotation of the drum 18 is accomplished comprises a driven shaft 30, a pinion 31 thereon, and a gear 32 journaled upon the shaft 19. As is more fully described in the prior application, the gear 32 has connected therewith, by suitable yielding connections 33, a ratchet wheel 34 which is adapted to be connected at intervals to a pawl 35 carried by the drum 18.

The pawl 35 is pivoted by a pin 36 to the drum 40 and is backed up by a cushioning member 37 which is mounted upon a bracket 38, as will be readily understood. A stop block 39 is also carried on the drum. The block 39 is pivoted on the pin 36 and held between the member 37 and a pin 39'. The stop block 39 is directly behind the pawl 35, as shown in Fig. 3. The pawl 35 has a tooth 40 which is adapted to engage with an abutment 41 yieldingly supported upon a trip arm 42. The pawl 35 and the associated parts 36, 37, 38, 45 39, and 39' are all secured to the drum by means of a plate 43 which is adjustably secured to one end of the drum by means of a pair of bolts 44 and 45 working in elongated slots in the plate 43, it being understood, of course, that the plate 43 is apertured to receive the shaft 19 and turns about this shaft as an axis in adjusting the plate 43 relative to the drum. The purpose of the adjustable mounting of plate 43 on the drum 18 is for setting the drum and its master sheet gripping mechanism with respect to the stop member 39 to obtain proper margins upon the copy sheets. This mechanism and its purpose are more clearly explained in the prior application and will not be further referred to.

60 65 The pawl 35 is yieldingly pressed toward engagement with the ratchet wheel 34 by a spring 46 secured to the pawl 35 by a pin 47 and secured to the plate 43 by a pin 48. In the stationary position of the drum, the pawl is lifted out of engagement with the ratchet wheel 34 by the portion 40 engaging the stop 41 on the trip lever 42, as hereinbefore described. This trip lever 42 is pivoted upon a stub shaft 49 mounted on the side frame 14 of the machine and has associated therewith a latch lever 50 which, as described in

the foregoing application, has a limited movement with respect to the trip lever 42 so that it may drop into the position shown in Fig. 3 with a shoulder 51 thereon engaging a shoulder 52 on the plate 43. The latch lever 50 thus operates to prevent rearward rotation of the drum 18.

The trip lever 42 has a projection 53 which is provided with a pin 54 adapted to engage a finger 55 on the latch lever 50 so that, when the trip lever 42 is lifted out of engagement with the portion 40 of the pawl 35, the pin 54 pressing upon the finger 55 will lift the latch lever 50 in order to prevent its striking the plate 43 in the subsequent rotation of the drum. A spring 56 is connected to the trip lever 42 by a pin 57 and is connected to the side frame 14 by a pin 58. A spring 59 is interposed between a shoulder 60 on the trip lever 42 and the latch lever 50 so as to urge the latch lever in a direction to bring the finger 55 against the pin 54. The trip lever 42 is actuated by a cross bar 61 which is supported at one end by an arm 62 pivoted at 63 to the side frame 15. At its other end, the cross bar 61 is connected to the trip lever 42 by a lever arm 64 which is secured by a pin 65 to a hub 66 for the trip lever 42. A stop pin 67 is mounted on the side frame 14 to limit the upward movement of the lever arm 64.

As shown and more fully described in the prior application hereinbefore mentioned, the hub 66 has a depending arm 68 which is connected by a pin 69 to a link 70, the pin 69 riding in a slot 71 of the bar 70. The link 70 links the trip lever 42 and its associated mechanism with a second set of trip and latch levers for controlling the positioning of the drum for replacement of master sheets. The link 70 is pivoted to an arm 72, which is bifurcated to receive the link 70, and has a pin 73 for securing the link 70 thereto. The arm 72 is fixed upon a shaft 74 which is journaled in the side frames 14 and 15. Adjacent the arm 72 the shaft 74 has pivoted thereon a trip lever 75 and a latching lever 76 which are substantially duplicates of the trip lever 42 and latch lever 50. The latch lever 76 is connected to the trip lever 75 by being pivoted on the same axis, and a limited amount of movement of the latch lever 76 with respect to the trip lever 75 is provided by a projection 77 on the trip lever extending over the latch lever and yieldingly held away from the latch lever by a spring 78. A pin 79 carried by a rearward extension 80 of the trip lever 75 engages a finger 81 on the latch lever 76 so that outward movement of the trip lever 75 with respect to the drum 18 will cause movement of the latch lever 76 therewith. A stop bracket 82 on the side frame 15 is adapted to engage a pin 83 upon the trip lever 75 to limit the inward movement of the latch lever and trip lever.

The trip lever 75 is connected to the shaft 74 upon which it is pivoted by means of a coiled spring 84 which at one end is connected to a pin 85 on a projection 86 which is formed on a hub 87 for arm 72 which is fixed to the shaft 74. The other end of the coiled spring 84 is secured to a pin 88 which is mounted upon the projection 80. The direction of winding the coiled spring 84 causes it to urge the trip lever 75 toward position to engage the stop portion 40 of the pawl 35. Thus the trip lever 75 and its latch lever 76 are used to stop the drum 18 in master sheet receiving position as more clearly explained in the prior application hereinbefore mentioned.

The mechanism for operating trip lever 75 and latch lever 76 comprises a bifurcated arm 75

90 fixed on the shaft 74 at the opposite side of the machine from the mechanism just described. The bifurcated arm 90 extends from a hub 91 that is also provided with a cam projection 92, the purpose of which will be more fully explained hereinafter. The bifurcated arm 90 is connected by a link 93 to a bifurcated projection 94 upon a hub 95 of a hand lever 96. The hand lever 96 is pivoted by means of the hub 95 to rotate about the shaft 19. The hub 95 carries a pair of rollers 97 and 98 which rollers are adapted to operate a pair of spreading cams 99 and 100. These cams 99 and 100 are pivoted upon stub shafts 101 and 102 suitably mounted on the side frame 15. A spring 103 coiled around the hub of the spreading cam 99 with one end fixed to a pin 104 on the spreading cam and the other end fixed to the frame 15 operates to urge the spreading cam 99 against the roller 97. A similar spring 105 on the hub of the spreading cam 100 and secured to the spreading cam by a pin 106, operates to urge this cam towards its roller 98.

The hand lever 96 may be placed in any one of the positions shown in Figs. 4, 5, and 6. When in the position shown in Fig. 6, the hand lever 96, through the medium of the link 93, positions the bifurcated arm 90 as shown in Fig. 6, and this so positions the shaft 74 to release the spring 84 and to move the trip lever 75 and the latch lever 76 out of the path of the pawl portion 40 and the plate 43. This is normal operating position for making copies on the machine.

Now, however, when the handle 96 is moved into the position shown in Fig. 2 and Fig. 4, the spring 84 pulls the trip lever 75 and its corresponding latch lever 76 into position to engage the pawl portion 40 as the drum rotates. When the portion 40 of the pawl 35 engages the stop portion of the trip lever 75, the drum is stopped in the position shown in Fig. 4 and held against rotation by the levers 75 and 76. It will be noted from an inspection of Fig. 4 that roller 97 engages in a depression 107 in the cam 99 while roller 98 engages a depression 108 in the cam arm 100.

Cam arms 99 and 100 are adapted to cooperate with a gripper control lever 109 which is keyed on a gripper shaft 110 that is mounted in the drum 18. Suitable gripper fingers 111, more fully described in the prior application, are secured upon the gripper shaft 110 and are adapted to grip a master sheet 112 against a surface 113 formed in the periphery of the drum. The arm 109 carries a roller 114 which is adapted to ride upon the cams 99 and 100 when they are spread out into the path of this roller. A spring 115, connected to the free end of the arm 109 and attached to the drum, acts to hold the arm 109 in position to close the grippers 111 except when the roller 114 is lifted by one of the cams 99 or 100.

It is evident from an inspection of Fig. 4 that, when the hand lever 96 has been moved to mid position as shown in Fig. 4 to stop the drum with the grippers 111 aligned with the master sheet tray 20, the rollers 97 and 98 being located in the depressions 107 and 108 of the spreading cams 99 and 100 do not engage the roller 114 so as to open the grippers 111. However, if the hand lever 96 is moved from the position shown in Fig. 4 to the position shown in Fig. 5, the rollers 97 and 98 are moved out of their respective seats at 107 and 108 in the spreading cams and spread these cams so that the cam 100 is lifted against the roller 114 causing counter-clockwise movement of the arm 109, as shown in Fig. 5, and a

resultant opening of the gripper 111. If the hand lever is then returned to the position shown in Fig. 4, the grippers 111 will again be closed due to the pull of the spring 115 upon the arm 109. Thus it is possible to bring the drum 18 to a stop without opening the grippers 111 in a position to align the gripping mechanism with the master sheet tray 20 and, as pointed out, the grippers 111 may then be opened and closed without releasing the drum for further rotation since the gripper opening movement is accomplished by movement in a direction which tends to hold the levers 75 and 76 in their drum stopping position.

In the normal operation of the machine, it is not necessary to stop the drum in alignment with the master sheet tray without releasing the used master sheet, so the operator, when he desires to replace the used master sheet, moves the hand lever 96 into the position shown in Fig. 7. This causes the roller 97 to move out the spreading cam 99 and, when the roller 114 rides over the spreading cam 99, it opens the grippers 111 in the manner indicated in Fig. 7 and releases the old master sheet. The drum, however, continues to rotate until it is stopped by the levers 75 and 76 engaging with the pawl portion 40 and the notch in the plate 43, respectively. At this time, that is at the time the drum comes to rest, the roller 114 is riding upon the surface of the spreading cam 100 and the grippers 111 are held in open position to receive a fresh master sheet.

It is often desirable to insert a sheet over a portion of the master sheet for the purpose of preventing the transfer of the data on that portion of the master sheet to a copy sheet. Since there is no adherence between a block-out sheet and master sheet used in this type of machine, it is necessary to secure the block-out sheet by some means. The present invention provides mechanism whereby a block-out sheet may be superimposed upon a master sheet 112 without disturbing the position of the master sheet.

The master sheet tray 20 is pivotally mounted with respect to the frame of the machine by a tie rod 116. A spring 117, secured at one end to the master tray 20 by a pin 118 and secured at its other end to a bar 119 on the side frame 15 of the machine, tends to tip the master tray 20 toward the drum 18. The master tray has a plate 120 secured to the under surface thereof and provided with a plurality of spring fingers 121. These fingers 121 are adapted to engage the master sheet 112 in the manner illustrated in Fig. 5 when the tray 20 is permitted to move toward the drum sufficiently to permit such engagement.

In the normal operation of the machine, however, the cam 92 mounted on the shaft 74 is held in the position shown in Fig. 6 so as to engage against a stop 122 provided on a bar 123 which depends from one side of the master tray 20. At one end of the master tray 20, a supporting disk 124 extends toward the drum 18, and the drum 18 has a notch 125 adjacent the grippers 111 and in line with the disk 124. Since the cam 92 is connected to the shaft 74, it is evident that, when the hand lever 96 is moved into the position shown in Fig. 7 to discharge a used master sheet, the master tray 20 will be permitted to move toward the drum because the cam 92 is moved away from the stop member 122 which normally holds the master tray 20 in raised position. The disk 124 then rides upon the surface of the drum close to the end thereof until the drum reaches

stop position with the master sheet grippers 111 aligned with the tray 20. At this point, the disk 124 drops into the recess 125 as will be readily understood.

5 Now in the operation of the machine to place a block-out sheet upon the master sheet 112, the operator, instead of moving the handle 96 all the way over to the position shown in Fig. 7, moves it only to the position shown in Fig. 4 so 10 that the grippers 111 are not opened by engagement of the spreading cam 99 with the roller 114. However, even this movement of the lever 96 causes the cam 92 to move away from the stop 122 and permits the tray 20 to tip toward the 15 drum. The disk 124 stops the tray 20 before the fingers 121 can engage the master sheet 112. This action of the disk 124 prevents the fingers 121 from smearing the master sheet. When the drum arrives in stop position, the disk 124 is 20 aligned with the recess 125 in the drum, and this permits the fingers 121 to engage the master sheet 112 and to hold it in place. The operator can then move the hand lever 96 to the position shown in Fig. 5 thereby opening the grippers 25 111 as shown in Fig. 5, and a block-out sheet 126 can be inserted without disturbing the position of the master sheet 112. The hand lever 96 can then be moved back to gripper closing or normal operating position.

30 As described in the application hereinbefore mentioned, the movement of the hand lever 96 back to normal operating position results in releasing the levers 75 and 76 thereby permitting the pawl 35 to engage the ratchet wheel 34 which 35 causes the drum to rotate around until it is stopped by the trip lever 42. In this position, the drum is ready for normal operation of feeding copy sheets.

In Figs. 9 to 13 inclusive, a slightly different 40 mechanism is shown for controlling the application of a block-out sheet. In this form of the invention, the hand lever 96 has pivoted thereon a bar 130 which bar has an elongated slot 131 that is engaged by a pin 132 mounted in the side 45 frame 15. The master sheet tray 20 has a pin 133 projecting from the side edge thereof over the bar 130 and adapted to ride on the top surface of this bar. The top surface of the bar 130 acts as a cam and is provided with a depressed 50 portion 134, the purpose of which will presently appear. In the normal running position of the machine, the hand lever 96 is in the position shown in Fig. 11 so that the pin 133 on the tray 20 rides upon the high portion of the bar 130 55 and holds the tray 20 in raised position away from the drum 18.

Now when it is desired to apply a block-out sheet over the master sheet held on the drum, the hand lever 96 is moved into the position 60 shown in Fig. 9 where it sets the stop mechanism hereinbefore described to stop the drum with the gripper 111 aligned with the master sheet tray 20. The operator usually sets this handle 96 while the drum is stationary in copy sheet 65 receiving position. He then taps the control bar 61 which releases the drum and permits it to rotate until it is stopped by the levers 75 and 76. It will be noted from Fig. 9 that the pin 133 and the bar 130 hold the tray 20 raised away from 70 the drum during the advance of the drum to this position. The operator then pulls the hand lever 96 over into the position shown in Fig. 10 which moves the bar 130 to the left as shown in Fig. 10 from the position shown in Fig. 9 and 75 brings the lower portion 134 of the top surface

of the bar beneath the pin 133. This permits the tray 20 to move down and to bring its fingers 121 against the master sheet 112 so as to hold the master sheet in position while the blockout sheet 126 is positioned beneath the grippers 111. 5 The grippers can then be closed and the master sheet tray 20 raised by moving the hand lever 96 back to its normal operating position. This also allows the drum to rotate to its own position and the desired number of copies can be 10 run off by operating the front control bar 61.

In many instances the operator may desire to make a few copies from a master sheet and then release it and save the master for future use. If the tray 20 were permitted to drop when 15 the hand lever 96 is moved to release the master, the tray would smear the back end of a long master sheet.

To avoid this danger, a mechanism is provided to lock the master tray 20 in raised position so that operation of the hand lever 96 will not effect movement of the tray to bring the fingers 121 against the drum. The tray may be locked by utilizing a pin 135 mounted in the side frame 15 and an aperture 136 in the side 25 of the tray 20. The pin 135 has a reduced portion 137 which passes through a member 138 screw threaded into the side frame 15 and is provided with a knurled head 139. The member 138 has an enlarged opening 140 housing a spring 30 141 which urges the pin 135 toward the tray 20. The reduced portion 137 of the pin 135 has a cross pin 142 therein which cross pin may be aligned with a slot 143 in the member 138 or aligned with a notch 144 in the outer end 35 of the member 138. When the pin 142 is in the slot 143, the spring 141 presses the pin 135 toward the aperture 136 in the tray 20. When the pin 135 is withdrawn and turned a quarter turn to align its cross pin 142 with the notch 144, the 40 pin 135 is held out of operative position so that the tray 20 is controlled by the bar 130.

In Fig. 14, a slightly modified form of mechanism is shown for controlling the actuation of the tray 20. In this form of the mechanism, 45 a portion 145 of the side wall of the tray 20 is extended downwardly and is adapted to engage a pin 146 fixed upon a projection 147 that is integral with the bifurcated arm 90.

While certain embodiments of the invention 50 have been shown and described, it is to be understood that it is capable of many modifications. Changes, therefore, in the construction and arrangement may be made without departing from the spirit and scope of the invention as disclosed 55 in the appended claims in which it is the intention to claim all novelty inherent in the invention as broadly as possible in view of the prior art.

Having thus described the invention, what I claim as new and desire to secure by Letters 60 Patent is:

1. In a duplicating machine, a rotatable drum, gripping means on said drum for securing the master sheet thereto, means for supplying copy sheets to said drum, a pressure roller for pressing copy sheets against the master sheet on said drum, moistening means for supplying a volatile solvent for the data on the master sheet and mechanism for supplying and attaching a block-out sheet over said master sheet comprising holding means operable to hold the master sheet in position upon the opening of said gripping means. 65

2. A duplicating machine comprising a frame, 70 a drum rotatable therein, gripping means to 75

clamp a master sheet on said drum, a pressure roller for pressing copy sheets against the drum, means to open said gripping means while the drum is stationary, and means operable to hold 5 a master sheet in said gripping means when said gripping means is open whereby a block-out sheet may be inserted in said gripping means without displacement of the master sheet.

3. A duplicating machine comprising a frame, 10 a drum rotatable therein, gripping means to clamp a master sheet on said drum, a pressure roller for pressing copy sheets against the drum, means to open said gripping means while the drum is stationary, and master sheet holding 15 means operable by said first named means to hold the master sheet in said gripping means against movement when said gripping means is open whereby a second sheet may be inserted into said gripping means over the master sheet.

20 4. In a duplicating machine, a rotatable drum, gripping means on said drum for securing the master sheet thereto, means for supplying copy sheets to said drum, a pressure roller for pressing copy sheets against the master sheet on said 25 drum, moistening means for supplying a volatile solvent for the data on the master sheet and mechanism for supplying and attaching a block-out sheet over said master sheet comprising holding means operable to hold the master sheet 30 in position upon the opening of said gripping means, said holding means comprising a member having a plurality of spring fingers for pressing the master sheet against the drum.

35 5. A duplicating machine comprising a frame, a drum rotatable therein, gripping means to clamp a master sheet on said drum, a pressure roller for pressing copy sheets against the drum, means to open said gripping means while the drum is stationary, and means operable to hold 40 a master sheet in said gripping means when said gripping means is open whereby a block-out sheet may be inserted in said gripping means without displacement of the master sheet, said master sheet holding means comprising a plate mounted 45 on said frame for movement toward and away from said drum, and having means thereon for pressing the master sheet against the drum.

6. In a duplicating machine, a rotatable drum, gripping means on said drum for securing the 50 master sheet thereto, means for supplying copy sheets to said drum, a pressure roller for pressing copy sheets against the master sheet on said drum, moistening means for supplying a volatile solvent for the data on the master sheet and 55 mechanism for supplying and attaching a block-out sheet over said master sheet comprising holding means operable to hold the master sheet in position upon the opening of said gripping means, and a hand lever for controlling said 60 holding means.

7. A duplicating machine comprising a frame, 65 a drum rotatable therein, gripping means to clamp a master sheet on said drum, a pressure roller for pressing copy sheets against the drum, means to open said gripping means while the drum is stationary, and means operable to hold 70 a master sheet in said gripping means when said gripping means is open whereby a block-out sheet may be inserted in said gripping means without displacement of the master sheet, said holding means comprising a master sheet tray pivoted on said frame and having a member 75 thereon for engaging the master sheet adjacent to said grippers.

8. A duplicating machine comprising a frame,

a drum rotatable therein, gripping means to clamp a master sheet on said drum, a pressure roller for pressing copy sheets against the drum, means to open said gripping means while the drum is stationary, and means operable to hold 5 a master sheet in said gripping means when said gripping means is open whereby a block-out sheet may be inserted in said gripping means without displacement of the master sheet, said holding means comprising a master sheet tray 10 pivoted on said frame and having a member thereon for engaging the master sheet adjacent to said grippers, spring means urging said tray toward the drum, and manually controlled mechanism for holding the tray away from said drum. 15

9. A duplicating machine comprising a frame, a drum rotatable therein, gripping means to clamp a master sheet on said drum, a pressure roller for pressing copy sheets against the drum, means to open said gripping means while the 20 drum is stationary, and master sheet holding means operable by said first named means to hold the master sheet in said gripping means against movement when said gripping means is open whereby a second sheet may be inserted into 25 said gripping means over the master sheet, said holding means comprising a plate, spring fingers on said plate, and means pivotally mounting said plate on the frame.

10. A duplicating machine comprising a frame, 30 a drum journalled for rotation therein, means to clamp one edge of a master sheet to said drum, means to press copy sheets against a master sheet on said drum, moistening means for supplying a solvent for the ink on said master sheet, 35 a control device for said clamping means whereby the clamping means may be opened and closed while the drum is stationary, and a second clamping means controlled by said device to hold the master sheet on the drum when said first named 40 clamping means is opened.

11. A duplicating machine comprising a frame, a drum journalled for rotation therein, means to clamp one edge of a master sheet to said drum, means to press copy sheets against a master sheet 45 on said drum, moistening means for supplying a solvent for the ink on said master sheet, a control device for said clamping means whereby the clamping means may be opened and closed while the drum is stationary, a master sheet tray 50 movably mounted in said frame and having its forward edge adjacent to said drum, spring means urging the forward edge of said tray toward the drum, a member on said tray for engaging the drum surface adjacent one end thereof whereby 55 to prevent the forward edge of said tray from pressing against the master sheet on the drum, said drum having a depression adjacent the clamping means to receive said member and permit the forward edge of the tray to drop down 60 on the master sheet when said clamping means is positioned to receive a sheet from said tray.

12. A duplicating machine comprising a frame, a drum journalled for rotation therein, means to clamp one edge of a master sheet to said drum, 65 means to press copy sheets against a master sheet on said drum, moistening means for supplying a solvent for the ink on said master sheet, a control device for said clamping means whereby the clamping means may be opened and closed while 70 the drum is stationary, a master sheet tray movably mounted in said frame and having its forward edge adjacent to said drum, spring means urging the forward edge of said tray toward the drum, said forward edge having a part for press- 75

- ing a master sheet against the drum, and means to prevent lowering of the said part onto a master sheet on the drum until the drum is stopped with said clamping means aligned with the master sheet tray.
13. A duplicating machine comprising a frame, a drum journaled for rotation therein, means to clamp one edge of a master sheet to said drum, means to press copy sheets against a master sheet on said drum, moistening means for supplying a solvent for the ink on said master sheet, a control device for said clamping means whereby the clamping means may be opened and closed while the drum is stationary, a master sheet tray movably mounted in said frame and having its forward edge adjacent to said drum, spring means urging the forward edge of said tray toward the drum, said forward edge having a part for pressing a master sheet against the drum, and means to prevent lowering of the said part onto a master sheet on the drum until the drum is stopped with said clamping means aligned with the master sheet tray, said last named means comprising a projection on the tray adapted to ride upon the surface of said drum.
14. A duplicating machine comprising a frame, a drum journaled for rotation therein, means to clamp one edge of a master sheet to said drum, means to press copy sheets against a master sheet on said drum, moistening means for supplying a solvent for the ink on said master sheet, a control device for said clamping means whereby the clamping means may be opened and closed while the drum is stationary, a master sheet tray movably mounted in said frame and having its forward edge adjacent to said drum, spring means urging the forward edge of said tray toward the drum, said forward edge having a part for pressing a master sheet against the drum, and means to prevent lowering of the said part onto a master sheet on the drum until the drum is stopped with said clamping means aligned with the master sheet tray, said last named means comprising a cam member movably mounted on the frame, and means on said tray adapted to ride on said cam member.
15. A duplicating machine comprising a frame, a drum journaled for rotation therein, means to clamp one edge of a master sheet to said drum, means to press copy sheets against a master sheet on said drum, moistening means for supplying a solvent for the ink on said master sheet, a control device for said clamping means whereby the
- clamping means may be opened and closed while the drum is stationary, and a second clamping means controlled by said device to hold the master sheet on the drum when said first named clamping means is opened, said second clamping means comprising a member mounted on said frame and spring pressed toward said drum, and means linked to said control device to hold said member away from the drum.
16. A duplicating machine comprising a frame, a drum journaled for rotation therein, means to clamp one edge of a master sheet to said drum, means to press copy sheets against a master sheet on said drum, moistening means for supplying a solvent for the ink on said master sheet, a control device for said clamping means whereby the clamping means may be opened and closed while the drum is stationary, and a second clamping means controlled by said device to hold the master sheet on the drum when said first named clamping means is opened, said second clamping means comprising a member mounted on said frame and spring pressed toward said drum, a cam bar movably mounted on the frame and connected to said control device, said member having a pin riding on said bar and holding the member away from said drum in one position of the bar and releasing the member for movement toward the drum in a second position of said bar.
17. A duplicating machine comprising a frame, a drum rotatably journaled therein, gripping means to clamp a master sheet on said drum, means to press copy sheets against a master sheet on said drum, a hand lever on the frame, stop means actuated by movement of said hand lever to one position to stop said drum with the gripping means closed, and means to open said gripping means operable by movement of said lever to a second position.
18. A duplicating machine comprising a frame, a drum rotatably journaled therein, gripping means to clamp a master sheet on said drum, means to press copy sheets against a master sheet on said drum, a hand lever on the frame, stop means actuated by movement of said hand lever to one position to stop said drum with the gripping means closed, and means to open said gripping means operable by movement of said lever to a second position, said frame having means thereon for holding a master sheet against the drum when said gripping means is opened after the drum is stopped.

ALFRED MARCHEV.
